UNITED STATES PATENT OFFICE.

ERNST ELIS FRIDOLF FAGERSTRÖM, OF SKARSATRA, NEAR STOCKHOLM, SWEDEN.

SELF-CENTERING CENTRIFUGE.

Application filed October 16, 1919. Serial No. 331,254.

To all whom it may concern:

Be it known that I, ERNST ELIS FRIDOLF FAGERSTRÖM, a subject of the King of Sweden, and a resident of Skarsatra, near Stockholm, in the Kingdom of Sweden, have invented certain new and useful Improvements in Self-Centering Centrifuges (for which I have filed an application for patent in Sweden February 8, 1918, No. 451/1918), of which the following is a specification, reference being had therein to the accompanying drawing.

In centrifuges for separating fluids it is, as known, of great importance that the centrifugal drum with its axle obtains a smooth and uniform movement and in order to accomplish this quite a number of constructions have been designed. Especially in such separators where the power is transmitted to the spindle of the centrifugal drum with gears or worm-wheel, the use of springy neck-journal-bearings has been employed in order to counteract the vibrations of the centrifugal drum when in motion. Such bearings are however inappropriate, amongst other reasons on account of their intricate design and petty strength and because the utilization of the centrifuge all together depends on that this bearing retains its original functional powers. In some known designs the drum-spindle is enclosed in a sleeve, in the lower part of which the end of the spindle is supported. This sleeve, cut up on the side, is in different ways made to swing near the point where the spindle engages the wormwheel and in order to center the centrifugal drum the sleeve is mostly provided with a springy bearing at the top or the bottom or it is supported by a standing flexible bar or spring.

The present invention relates to an arrangement by which, in employing such a spindle sleeve, in itself known heretofore, the self-centering of the centrifugal drum is effected without the use of a springy bearing or generally springs or separate parts of any kind.

On the accompanying drawing Fig. 1 is a longitudinal section through a hand-separator showing a form of this arrangement.

Fig. 2 shows a modification of the arrangement and Fig. 3 is a sectional view on line A—A in Fig. 1. The worm 2 for the centrifugal drum is journaled in and supported by a stationary sleeve 3. This sleeve is as usual cut out at one side, so that the worm-wheel 4

may enter and engage the worm. The sleeve is mounted in a chamber 5 in the machine standard 10 and is laterally supported by a flange 6 projecting from the sleeve against the walls of the cylinder in a plane perpendicular to the spindle and in a plane with the longitudinal axis of the worm-wheel. Through this circular flange the spindle is retained in suitable contact with the worm-wheel when the centrifugal drum sways but the flange does not support the sleeve. The spindle and the sleeve are supported at their lower end by the foot of the standard and this lower end of the sleeve and the spindle slide when the centrifugal drum sways, thereby causing the sleeve-end to be laterally dislocated against a surface of such an inclination relative to the longitudinal axis of the spindle that the sleeve will tend to slide back and regain its centered position. The end of the sleeve is mainly supported against the bottom of the room 5 and is engaged by a recess 8, the shape of which about corresponds to the conical, elliptical or other shaped bottom end of the sleeve, but it may also have a different form from the latter.

By choosing a suitable angle of inclination of the sloping surface the end of the spindle, on account of the weight of the centrifugal drum and the sleeve, and the downward acting pressure on the spindle, will tend to slide back to its normal position in the recess 8 and this tension counteracts the sway of the centrifugal drum and brings it back to its originally adjusted position.

The above described arrangement can be modified in a way shown in Fig. 2 where the inclined surface consist of a central recess 9 in the end of the sleeve, which recess rests on an elevated portion at the foot of the standard. In order to limit the above mentioned sliding of the sleeve-end and thereby the sway of the centrifugal drum the recess 8 and the elevated portion 9 respectively are located in a cavity at the bottom of the chamber 5, the walls of which will prevent a sway of undesired magnitude of the sleeve-end. This may also be accomplished by projections or in a similar way.

By such an arrangement a self-centering centrifuge is provided without such a delicate part as a springy bearing, besides which the centrifuge is easily taken to pieces and can easily be arranged for self-

lubrication if the inner chamber of the standard is closed at the bottom so that the worm-wheel will raise the oil from the bottom of the chamber.

5 Having now described my invention, what I claim as new and desire to secure by Letters Patent is:

1. In a device of the character described, the combination with a centrifugal drum, 10 and a chambered standard of a sleeve arranged within the chamber of the standard and supported at its lower end thereby, a bearing for the lower end of the sleeve constructed to permit the sleeve to have a 15 longitudinal as well as a lateral movement when the centrifugal drum sways and to slide back and regain its centered position, a worm spindle carrying the centrifugal drum and rotatably mounted at both its ends in 20 the sleeve and being movable longitudinally as well as laterally with said sleeve, a peripheral flange on the sleeve having a bearing against the inner wall of the standard, and a vertically-arranged worm wheel 25 engaging the worm spindle, the longitudinal axis of the worm wheel coinciding with the said flange, as and for the purpose set forth.

2. In a device of the character described, 30 the combination with a centrifugal drum and a chambered standard, of a sleeve arranged within the chamber of the standard, said sleeve being cut out at one side and having a peripheral flange bearing against 35 the inner wall of the standard, the lower end of the sleeve being seated in a recess in the standard, said recess having a shape corresponding to the shape of the lower end of the sleeve, the bearing surface of the recess

having such an inclination relatively to the longitudinal axis of the spindle that the sleeve will always tend to slide upon the bearing surface and regain its centered position, the said sleeve being also adapted to have a lateral movement in said recess, a 45 worm spindle rotatably mounted at both its ends in the sleeve and being movable longitudinally as well as laterally with the sleeve, and a vertically-arranged worm wheel mounted upon an axis arranged in a horizontal plane coinciding with the flange on the sleeve, said worm wheel projecting through an opening in the standard and the opening formed in the sleeve. 50

3. In a device of the character described, 55 the combination with a centrifugal drum and a chambered standard, of a sleeve arranged within the chamber of the standard and supported at its lower end thereby, a bearing for the lower end of the sleeve constructed to permit the sleeve to have a longitudinal as well as a lateral movement when the centrifugal drum sways and so slide back and regain its centered position, a worm spindle carrying the centrifugal drum and 60 rotatably mounted at both its ends in the sleeve and being movable longitudinally as well as laterally with said sleeve, a peripheral flange on the sleeve having a bearing against the inner wall of the standard, a 65 vertically-arranged worm wheel engaging the worm spindle, the longitudinal axis of the worm wheel coinciding with the said flange, and means to limit the lateral movement of the sleeve. 75

In witness whereof I have hereunto signed my name.

ERNST ELIS FRIDOLF FAGERSTRÖM.
